The ornamental design for a camera assembly, as shown and described.

DESCRIPTION

A portion of the disclosure of this patent document contains material which is subject to copyright protection. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top perspective view of a camera assembly;
FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines depict portions of the camera assembly in which the design is embodied that form no part of the claimed design.
